Primary Examiner — T Chase Nelson

Assistant Examiner — Dana K Weiland

(74) Attorney, Agent, or Firm — Stephen J. Weyer, Esq.;
 Stites & Harbison, PLLC(57) **CLAIM**

The ornamental design for a remote control, as shown and described.

DESCRIPTION

Remote control

2.1 is a perspective view of a remote control showing the new design;

2.2 is a front view thereof;

2.3 is a left side view thereof;

2.4 is a right side view thereof;

2.5 is a bottom view thereof; and

2.6 is a top view thereof.

The broken lines show portions of the remote control that form no part of the claimed design.

1 Claim, 6 Drawing Sheets(56)
